CLAIM

We claim the ornamental design for a boat, as shown and described.

DESCRIPTION

FIG. 1 is a front view of our design for a boat;

FIG. 2 is a rear view thereof;

FIG. 3 is a top view thereof;

FIG. 4 is a bottom view thereof;

FIG. 5 is a right side view thereof; and,

FIG. 6 is a left side view thereof.

The broken lines depict portions of the article that form no part of the claimed design.
